[57] CLAIM

The ornamental design for a combined hearing aid volume control knob and adapter ring, as shown and described.

DESCRIPTION

FIG. 1 is a perspective view of a combined hearing aid volume control knob and adapter ring showing my new design;

FIG. 2 is a side view thereof;

FIG. 3 is a top plan view thereof;

FIG. 4 is a bottom plan view thereof;
The dot and dash line portions of the drawing are included to show environmental structure not claimed as part of my ornamental design.

FIG. 1.

FIG. 2.

FIG. 3.

FIG. 4.
